PUMP

Filed Sept. 22, 1926

UNITED STATES PATENT OFFICE

LYNNE D. BAIRD, OF TULSA, OKLAHOMA

PUMP

Application filed September 22, 1926. Serial No. 136,986.

My invention relates to pumps and more particularly to pumps for use in oil wells and similar places.

It is a purpose of my invention to provide a pump of the above mentioned character comprising a hollow piston member, an operating member having a valve member thereon and means for mounting the piston on the support in such a manner that relative sliding movement is provided between the piston and the valve member. This is preferably accomplished by providing the valve stem on the supporting member with a portion upon which the piston is slideable and by providing means thereon to limit the sliding movement of the piston in opposite directions, one of the means being preferably adjustable to adjust the range of movement of said piston.

It is a further purpose of my invention to provide a new and improved packing in an oil well, or similar, pump mounted on the piston and engaging the barrel of the pump, said packing comprising a tubular member having means for clamping the ends thereof to the exterior of the piston and having means for admitting fluid under pressure between the packing and the piston to expand the packing against the barrel.

Other objects and advantages of the invention will appear as the description of the accompanying drawings proceeds. However, I desire to have it distinctly understood that I do not intend to limit myself to the exact details shown or described. But that I intend to include as part of my invention all such obvious changes and modifications of parts as would occur to a person skilled in this art and as would fall within the scope of the claim.

In the drawings:

Fig. 1 is a fragmentary sectional view of the lower portion of an oil well showing my improved pump applied thereto.

Fig. 2 is a fragmentary sectional view of the pump on a larger scale, and

Fig. 3 is a perspective view, partly broken away, of portions of the piston showing the same in disassembled condition.

Referring in detail to the drawings:

My improved pump is shown as being mounted within the barrel 10 which is pro-

vided in the casing 11 that is seated in the usual manner upon the cap rock 12 above the oil sand 13. Said barrel 10 is provided with the usual strainer member 14 located below the level of the oil 15 in the hole 16, said strainer being connected with the barrel 10 by means of a coupling 17 which carries the usual standing valve member 18.

Extending into the pump barrel 10 is a sucker rod 19 or other supporting member for actuating the pump. Said member 19 may be provided with an internally threaded socket 20 which receives the correspondingly threaded end portion 21 of the valve supporting member 22. The member 22 is provided with an enlargement at 23 forming a shoulder 24 thereon facing upwardly and has a bevelled wall portion 25 merging with the reduced portion 26. The reduced portion 26 of the member 22 serves as a valve stem having a threaded lower end portion 27 upon which the valve member 28 having a bevelled face 29 is mounted. The valve member 28 is held in adjusted position by means of a castellated nut 30 which is held in adjusted position by means of a cotter pin 31 in the usual manner.

The upper crown member 32 of the hollow piston is slidably mounted upon the unthreaded portion 33 of the member 32 between the shoulder 24 and the stop member 34 having screw-threaded engagement with its screw-threaded portion 35 of the member 22, the same being held in adjusted position by means of a lock nut 36, also engaging with the screw-threaded portion 35. The member 36 and upper crown member 32 may be provided respectively with annular ratchet teeth or corrugations 37 and 38 whereby the same may be gripped by a suitable fishing tool when this becomes necessary.

The crown member 32 is provided with an enlarged body portion 39 which has longitudinally extending slots 40 leading into the grooves 41, aligning therewith. The slots 40 lead into the central chamber or recess 42 provided in the enlarged body portion 39 and said enlarged body portion 39 is preferably provided with an internally threaded end portion 43 which is adapted to screw-thread-

edly engage with the externally threaded end portion 44 of the tubular body portion 45 of the hollow piston. The lower end portion of the tubular body portion 45 is also provided with an externally screw-threaded portion 46 that engages with the internally screw-threaded end portion 47 of the lower crown member 48, said lower crown member 48 having a chamber 49 within the same to which the slots 50 lead. Thus, when the valve is in the position shown in Fig. 2, connection is established between the space 51 below the piston and the space 52 above the piston in the barrel 10. This is the position of the parts on the down stroke of the piston. On the up stroke of the piston, the upward movement of the member 19 will carry the member 22 with the same, the piston lagging behind and as a result, the valve 29 will engage with a valve seat 53 on the valve ring 54, having a flange 55 seated between the shoulder 56 on the member 48 and the lower end portion of the member 45, thus closing the passage 57 through the tubular member 45 and lifting the liquid, in the same and above the same in the space 52 upwardly. When the down stroke of the piston again takes place, the same being actuated by the downward movement of the member 19, the tendency will be for the piston to lag behind the member 22, thus causing the valve 28 to be unseated and moved to the position shown in Fig. 2, whereupon the liquid in the space 51 below the piston will be admitted to the piston as the same moves downwardly.

In order to obtain the proper functioning of the pump described above, it is necessary that a packing be provided which will firmly grip the inner wall portion of the barrel 10. Said packing preferably comprises a tubular or sleeve-like member 58 which may be made of any suitable packing material that has the desired flexibility and resiliency, said member being preferably molded in the form shown in Fig. 3 with slightly convex wall portions 59 and substantially cylindrical end portions 60 with a shoulder 61 between said portions. The end portions 60 at one end of the packing member 59 preferably engage in grooves 62 provided in the member 45, said member 45 having a thickened portion 63 that has an overhanging flange 64 to provide such grooves 62. The opposite end portion 60 of the member 59 is engaged in a groove 65 formed between the overhanging flange portion 66 on the internally screw-threaded member 67 and the outer face of the tubular member 45. The member 67 has screw-threaded engagement with the threaded portion 44 and is held in adjusted position due to the engagement of the threaded end portion 43 of the member 32 with said threaded end portion 44 as shown in Fig. 2. It will be seen that the position of the member 67 relative to the enlargement 63 can be

varied due to the screw-threaded connection so as to obtain the proper clamping engagement with the ends 60 of the member 59 at opposite ends thereof. The tubular member 45 is further provided with a series of openings 68 which lead from the passage 57 into the space between the packing member 59 and the outer face of the tubular member 45. Thus the fluid under pressure within the barrel 10 and within the passage 57 will exert a force against the inner wall of the packing 59 causing the same to be firmly pressed into engagement with the inner face of the barrel 10 through substantially the entire length thereof with a substantially uniform pressure; thus a very effective seal is provided between the pump barrel and the piston.

It will be noted that in case of breakage of the valve member, the same will not become disassembled from the piston and furthermore, that the piston can be withdrawn in case any breakage occurs or renewal of the packing is necessary by an upward movement of the member 19, without the use of fishing tools, due to the fact that the shoulder 24 will engage with the shoulder 69 provided on the inner face of the member 32 where the reduced bore 70 opens into the opening 42. Thus, even if the valve member is detached, the piston will be drawn upwardly along with the other parts of the device by upward movement of the sucker rod or other support 19.

What I claim and desire to secure by Letters Patent is:—

A pump of the character described including a barrel, a piston including a tubular body, crowns at the ends of the body, a valve seat retained to the body by the lower crown, a stem extending through the body, the crowns and the valve seat, a valve on the stem cooperative with said seat, a stop member on the stem engageable with the upper crown to limit upward movement of the stem, and a stop member adjustable on the stem and engageable with the upper crown to limit downward movement of the stem.

In testimony whereof I affix my signature.
LYNNE D. BAIRD.
